His Atty.

UNITED STATES PATENT OFFICE.

AUGUST BOUCHERY, OF BROOKLYN, NEW YORK.

ATTACHMENT-PLUG.

1,258,646.

Specification of Letters Patent. Patented Mar. 12, 1918.

Application filed January 22, 1915. Serial No. 3,701.

To all whom it may concern:

Be it known that I, AUGUST BOUCHERY, a citizen of the United States, residing in the borough of Brooklyn, in the county of 5 Kings, city and State of New York, have invented new and useful Improvements in Attachment-Plugs, of which the following is a specification.

This invention relates to attaching plugs 10 to engage in the commercial screw threaded socket or the like to connect electrical conductors, and it is the object of the invention to provide an attaching plug of this character which may be securely connected to 15 and disconnected from the screw threaded shell of a socket or the like by a longitudinal or axial movement, and without the necessity of rotating the plug or shell, and to provide a plug of this character which is 20 simple in construction, having a minimum number of parts, durable and efficient in operation.

In the drawings accompanying and forming a part of this specification, Figure 1 is 25 a sectional side elevation of a plug illustrating an embodiment of my invention; and

Fig. 2 is a perspective view of the means to secure the plug in a socket or the like.

Similar characters of reference designate like parts throughout the different views of the drawing.

The embodiment of my invention shown in the drawing comprises a block of insulating material 15, preferably circular in cross section, having a contact 16 at one end in the form of a headed screw to make electrical contact with an electric contact in a socket or the like (not shown) and to which contact 10 an electric current conductor 17 is connected, said conductor engaging in a longitudinal channel 18 in the block, or it may consist of a bore, extending from the contact 16 to the opposite end of the block. A second 15 contact in the form of a resilient finger or fingers 43 having screw threaded sections 45 are secured at one end of the block, as at 44, to extend parallel with the side of the block and engage in a longitudinal channel 20 therein, and to which contacts 43 the other electric conductor 21 is connected.

These contacts 43 are so constructed that the ends 45 will normally spring laterally and stand away from the body portion of the plug, but this movement is limited by a 55 flanged portion 46 at the ends and adjacent the screw threads 45 engaging over an annular flange 42 formed by an annular recess 41 in the block. The block or body portion has a cap 47 with a central opening communicating with the block recesses 18, 20 for the passage of the current conductors.

To connect the plug to a socket or the like it is only necessary to push the plug longitudinally into the socket, the resilient fingers 65 43 readily yielding due to the inherent tension thereof and will yieldingly but firmly engage with the screw threads of said socket or the like and maintain them connected, the contact 16 engaging with the contact in the bottom of the socket connected to a current conductor, and the circuit being completed through the resilient fingers 43 contacting with the screw threaded shell in the socket to which the other conductor is connected.

Having thus described my invention, I claim:

1. In an attachment plug, the combination of a block of insulating material having a terminal contact at one end and a 80 recess in the side; and a resilient finger to constitute the other terminal contact of the plug, said finger being secured to the block at one end to extend longitudinally of the block in line with the recess and tensioned 85 so that the free end will spring laterally, the free end of the finger having a part to co-operate with the block in line with the recess to limit the outward movement of the finger, and said finger being constituted to co-operate with the threaded shell of a socket, substantially as and for the purpose specified.

2. An electric attachment plug comprising a block of insulating material having a 95 contact at one end; a longitudinal recess in the side thereof; a recess in the block to form a shoulder at one end of the longitudinal recess; a resilient metallic band to constitute another terminal contact of the 100 plug secured at one end to the block to engage and have yielding movement in the

longitudinal recess and tensioned so that the free end will normally spring laterally of the block and having a flange at the free end to engage over the shoulder formed at 5 the end of the longitudinal recess in the block, and said band having a protruding part to coöperate with the screw threads of

a socket to retain the plug therein, substantially as and for the purpose specified.

AUGUST BOUCHERY.
